TEMPER CONTROL FOR MOLDING SAND

Theodore K. Rigen, Elmira, N. Y.

Application August 22, 1947, Serial No. 770,118

2 Claims. (CL 318—264)

1

The present invention relates to a temper control for molding sand, and more particularly to a means for automatically controlling the addition of water to molding sand in order to maintain a desired percentage of water content.

In one system for tempering foundry sand which is commonly employed, the sand is transported to the molder by means of a conveyor belt, and the necessary water to temper the sand is added while it is being so transported. Usually in this system, the belt is formed of a plurality of sections in order to facilitate the mixing and aeration of the same as it is transferred from one belt to another.

As the operation is usually performed, the amount of water added is determined empirically by an experienced operator who feels the sand from time to time, judges the percentage of water and manually controls a valve in a water system to regulate the sprinkling of the water on to the moving belt.

It is an object of the present invention to provide a novel system for adding water to molding sand, which is arranged to automatically maintain the desired percentage of moisture with a high degree of accuracy.

It is another object to provide such a device which utilizes the electrical conductivity of the moistened sand as a gauge of the percentage of water in the sand.

It is another object to provide such a device which can be readily adjusted to provide any desired proportion of water in the sand.

It is another object to provide such a device including a pair of electrodes adapted to be inserted in the tempered sand in spaced relation, and means for opening a sprinkler valve when the resistance of the sand between the electrodes rises above a predetermined value, and for closing the valve when said resistance falls below said value.

It is a further object of the invention to provide such a device including means whereby when said resistance between the electrodes exceeds a predetermined value, such as might happen when there is no sand on the conveyor belt, the water supply valve will be quickly and completely closed.

Further objects and advantages will be apparent from the following description taken in connection with the accompanying drawing which illustrates diagrammatically a preferred form of the invention.

In the drawing, numerals 1 and 2 indicate electrodes or "feelers" of any suitable form adapted to be inserted in the molding sand on a travelling belt after it has passed the sprinkling system for adding water to the sand. Inasmuch as the con-

2

veying and sprinkling system is well known in the art and forms no part of the present invention, illustration thereof is deemed unnecessary.

Electrode 1 is grounded as indicated at 3 and electrode 2 is connected to the secondary 4 of a transformer 5 the primary 6 of which is energized from a suitable source of alternating current such as the usual 110-volt power line indicated at X, Y. A second similar transformer 7 has one end 10 of its secondary 8 connected to the secondary 4 of transformer 5 at the point 9. The primary 11 of transformer 7 is also connected to the same source of alternating current as the primary 6 of transformer 5, and the connections of the secondaries of these transformers are such that the connected ends of the secondaries are at all times 180 degrees out of phase.

The free end of the secondary 8 of transformer 7 is connected to the ground through a variable 20 resistor 12. It will be appreciated therefore that the predominant phase of the voltage existing between the point 9 and ground is dependent upon the relative value of the resistor 12 and the resistance of the path through the sand between 25 the electrodes 1 and 2. In other words, the instantaneous voltage between the point 9 and ground will be the algebraic sum of the instantaneous voltages across the secondaries 4 and 8.

The signal appearing thus at the point 9 is expressed across a resistor 10 and applied to the grid 13 of a vacuum tube 14 whereby the signal is amplified, and the output of tube 14 is coupled by a transformer 15 to a push-pull stage of amplification comprising tubes 16, 17. The output of tubes 16, 17 is transmitted through a transformer 18 to the armature 19 of a reversible motor 21 which actuates the sprinkler valve 20 for controlling the addition of water to the molding sand.

40 The field 22 of motor 21 is energized by an alternating current of the same frequency as the amplified signal impressed on the armature. For this purpose, an oscillator 23 preferably the same source X, Y of alternating voltage which energizes the primaries of transformers 5 and 7 is arranged to impress a signal on the grid 24 of an amplifying tube 25 by means of a variable gain control 45 26. The output of tube 25 is coupled by a transformer 27 to a push-pull stage of amplification including tubes 28, 29, and the output of this stage is transmitted through transformer 31 to the field 22 of the motor. Since the alternating current supplied to the field 22 of the motor is thus of the same frequency as the energization of 50 55 the armature thereof, rotation of the motor will

obviously depend upon the phase relationship between the armature and field, which phase relationship is dependent upon the relative predominance of the voltage generated in the secondaries 4 and 8 of transformers 5 and 7 respectively.

In the operation of the device as so far described, the signal developed at the point 9 is expressed across the grid resistor 10 and hence produces an alternating voltage on the grid 13 of tube 14. After being amplified by this tube the signal is fed through transformer 15, the push-pull stage 16, 17 and hence through transformer 18 to the armature 19 of the control motor 21. Since the field 22 of the control motor is being concurrently energized at the same frequency, the direction and angular velocity of the armature of the control motor will be a function of the amplitude of the signal transmitted by transformer 18, and the phase relation between this signal and the signal transmitted by the transformer 31 to the field 22.

As the resistance of the moistened sand between the electrodes 1, 2 is increased from a low value to equality with the value of resistor 12, the motor will change from one direction of rotation at full speed, through a stalled condition, to full speed in the opposite direction. If the value of resistor 12 is set so as to equal twice the resistance of the path between the electrodes 1, 2 when the sand is correctly tempered, the point 9 will then be 90 degrees out of phase with the oscillator 23, and consequently the armature 19 of the motor will be 90 degrees out of phase with the field. There will therefore be no rotation of the motor under this condition and consequently no change in the opening of the valve controlled by the motor.

If the sand arriving at the electrodes 1, 2 has insufficient water content, the phase relation between the point 9 and ground will shift in such a direction as to cause the armature 19 of the motor to rotate in a direction to open the sprinkler valve wider. Conversely, over-damped sand will similarly cause the armature of the motor to rotate in the opposite direction so as to reduce the opening of the sprinkler valve.

The structure thus far described provides an accurate means of controlling the percentage of water in the sand as long as the electrodes 1, 2 are covered by the sand. Inasmuch however as it will sometimes happen that the supply of sand on the conveyor is interrupted, it is necessary to provide means for rapidly closing the sprinkler valve when the resistance of the path between the electrodes 1, 2 becomes inordinately high. For this purpose, means are provided for reversing the phase relation of the field of the motor when the electrodes 1, 2 are substantially open-circuited.

As here shown this means includes a tube 32 the grid 33 of which receives the signal from the point 9 through an adjustable gain control 34. The cathode 35 of tube 32 is biased beyond cut-off by means of a voltage divider 36, 37 whereby the tube ordinarily transmits no signal. The output of tube 32 is coupled through a condenser 38 to a second amplifier tube 39 having in its plate circuit a filter comprising a condenser 41 and choke 42. The principal purpose of the tube 39 is to isolate the filter from the cut-off characteristics of the tube 32. In other words, when there is sufficient signal appearing on the grid 33 to cause the tube 32 to transmit a signal, the transmitted signal is merely a series of pulses, and the tube 39 and filter 41, 42 by its "fly-wheel" effect oper-

ate to change these pulses into a signal which approaches a sine wave.

This reconstructed signal is then impressed through a coupling condenser 43 and a resistor 44 on the grid 24 of oscillator tube 25, this signal being thus expressed across the gain control 26 of oscillator 23 and resistor 45 in series therewith.

The total signal existing on the grid 24 of tube 25 is therefore the algebraic sum of the signal from the oscillator 23 and from the filter. These signals are arranged to be of opposite phase when the current flowing through the secondary 8 of transformer 7 predominates over the current flowing through the secondary 4 of transformer 5, or in other words, when the resistance between electrodes 1, 2 is greater than the setting of the variable resistor 12.

The gain controls 34 and 26 are so adjusted in relation to the co-operating elements of their circuits that when the electrodes 1, 2 are open-circuited, the signal then transmitted through the tube 32 and the filter is at least twice the amplitude of the signal from the oscillator 23. The tube 25 therefore under those circumstances has an out-put approximately the same in amplitude as before, but opposite thereto in phase. This signal, when transmitted through transformer 27, amplifier 28, 29 and transformer 31 energizes the field 22 of the motor 180 degrees out of phase from its normal energization.

The high resistance between the electrodes 1, 2 causes energization of armature 19 of the motor in such phase that the motor would normally open the sprinkler valve, but since the field is now reversed in phase, the motor closes the valve. When electrodes 1, 2 are open-circuited, the armature current is approximately twice its normal high-speed value, and since the field voltage is substantially the same as its normal value, the motor will operate to close the sprinkler valve much faster than its movement in normal operation. This will prevent flooding an empty sand belt.

Although but one embodiment of the invention has been shown and described in detail, it will be understood that other embodiments are possible without departing from the scope of the invention.

50 What is claimed is:

1. In an electronic control for tempering molding sand, a pair of electrodes arranged to be submerged in spaced relation in the moistened sand, valve means for controlling the addition of water to the sand, a reversible motor for actuating said valve means, and control means responsive to an increase in resistance of the sand between the electrodes above a pre-set value for causing rotation of the motor to open the valve means, and responsive to a decrease in said resistance below the preset value to cause rotation of the motor to close the valve means, in which the control means includes means for supplying alternating current of a fixed frequency to the field of the motor, means for supplying alternating current of the same frequency to the armature of the motor, and means for varying the phase relation between the armature and field in accordance with deviations of the resistance of the sand between the electrodes from the pre-set value; including further, means for inverting the phase of the field responsive to an open circuit condition between said electrodes.
2. In an electronic control for tempering molding sand, a pair of electrodes adapted to be in-

serted in fixed spaced relation in the sand, means for passing an alternating current of fixed frequency through said electrodes, a variable resister, means for passing the same alternating current through the variable resister, means so connecting the circuit containing the electrodes to the circuit containing the variable resister that the currents of said circuits are 180° out of phase at the point of junction; a sprinkler valve motor having an armature and a field, means for energizing the field by an alternating current of the same frequency as said first mentioned alternating current, and means for amplifying the signal appearing at said junction point and en-

ergizing the armature thereby; including further means for reversing the phase relation of the field and armature responsive to an open-circuit between said electrodes.
